WITNESS:

ATTORNEY

Patented Feb. 15, 1927.

UNITED STATES PATENT OFFICE.

EDWIN W. BOYER, OF THORNTOWN, INDIANA.

FEEDER.

Application filed May 27, 1925. Serial No. 33,255.

This invention relates to improvements in feeders, drinking fountains and the like for poultry use and contemplates the provision of a base having standards extending 5 upwardly from diametrically opposite sides upon its upper side and which have secured to their inner sides and adjacent their upper ends, a circular band or rim which is adapted to receive an inverted jar or receptacle there- 10 between in order that the same may be held in this position while its neck will be positioned within a bowl or the like arranged upon the upper side of the base or platform.

Another object of my invention is the 15 vision of pairs of spring clips arranged upon the band or rim and which are adapted to have their upper ends engaging the outer side walls of the receptacle or jar while their lower ends are inwardly offset and engage 20 the shoulder of the jar or receptacle in order that the necks thereof will be spaced from the bottom of the bowl or the like arranged upon the top of the base.

With the above and other objects in view, 25 the invention further includes the following novel features and details of construction, to be hereinafter more fully described, illustrated in the accompanying drawings and pointed out in the appended claims.

30 In the drawings:—

Figure 1 is an elevation of my invention. Figure 2 is a transverse section taken on line 2—2 of Figure 1.

Figure 3 is a vertical sectional view.

35 Figure 4 is a similar vertical sectional view taken upon the opposite side of my invention.

Referring to the drawings in detail, where- 40 in like characters of reference denote cor- responding parts, the reference character 10 indicates a supporting base or platform hav- 45 ing a pair of standards 11 arranged upon the top of the supporting base or platform 10 and which includes inwardly offset portions 12 and outwardly extending lower portions 13 which lie flush with the upper side of the supporting base or platform 10 and which are rigidly secured thereto through the instrumental- 50 y of rivets 14 and have their opposite ends bent upon themselves as at 15 within slotted portions provided in the base 10. A bowl 16 is arranged upon the top of the supporting base or platform 10 and having its opposite sides engaging the inner sides 55 of the inwardly offset portions 12 of the standards 11 while a pair of retaining clips

17 which have their lower portions riveted or otherwise secured as at 18 at diametrical- 60 ly opposite sides of the supporting base or platform 10 and have their lower free ends extending through slotted portions provided in the supporting base or platform and lying flush with the bottom of the supporting base or platform 10 as clearly illustrated at 19 in Figure 4 of the drawings, while the upper 65 ends of the retaining clips 17 are inwardly offset as at 20 and which engage the upper edges or periphery of the bowl 16 whereby the same is held against lateral movement 70 in all directions. Secured to the inner sides and adjacent the upper ends of the standards 11 is a flat band or rim 21 having its op- 75 posite edges bent inwardly and lying flush with its inner side walls.

A pair of substantially inverted U-shaped 80 wires having their lower free end portions extending through channels provided be- 85 tween the rear sides of the band or rim 21 and their inwardly bent edges while the lower free ends of the substantially inverted U-shaped wires 22 are inwardly offset as at 90 23 while their upper ends are bent inwardly in a similar manner. An inverted receptacle or jar 24 is adapted to have its neck 25 and shoulders 26 extend between the inner side walls of the flat band or rim 21 and adapted to have the substantially inverted U-shaped wires 22 engage their outer sides while the inwardly offset portions 23 upon the lower free ends of the wire strips 22 will engage 95 the shoulders 26 of the jar or receptacle 24 in order that the neck 25 thereof will be held in spaced relation with respect to the bottom of the bowl 16.

In the mode of operation of the present 95 invention it is clearly apparent and mani- 100 fest that owing to the inwardly offset por- tions 12 provided upon the inner sides of the standards 11 that the diametrically opposite side of the bowl 16 will be engaged to hold 105 the same against lateral movement in one direction while the retaining clips 17 will restrict its movement and hold the same rigidly against the upper side of the sup- 110 porting base or platform 10 in order that such bowl 16 will not become readily dis- engaged from the base 10, and owing to the arrangement of the flat band or rim 21 upon the inner sides and adjacent the upper ends 110 of the standards 11 and so contortioned as to receive the jar or reservoir 24 between its inner side walls and adapted to support

thereon a pair of the substantially inverted U-shaped wires 22 which in turn engage the outer side walls of the jar 24 and which in turn have their inwardly offset free end portions 23 engaging the shoulders 26 of the jar 24 in order that the neck 25 thereof will be arranged and held in spaced relation with respect to the bottom of the bowl 16 in order that the contents of the jar or reservoir 10 24 will be allowed to seek its level within the bowl 16 and owing to the restricted space between the outer sides of the neck 25 of the receptacle or jar 24 and the inner edges of the bowl 16 that when this device is used for 15 poultry feeding and the like, that the chickens will not be permitted to enter the bowl and pollute the contents of the bowl 16.

It is further to be noted that in the process of filling or refilling the jar or reservoir 20 24, that the said jar is arranged in an upright position, after which the neck 25 thereof is received within and lying flush with the bottom of the bowl 16, obviously the bowl 16 is held rigidly upon the supporting base or platform and the band or 25 rim 21 is received upon the jar or reservoir 24; the jar or reservoir 24 is then inverted and raised to the positions as clearly illustrated in Figures 3 and 4 of the drawing so 30 that the contents thereof may flow into the bowl 16.

The invention is susceptible of various changes in its form, proportions and minor details of construction, and the right is 35 herein reserved to make such changes as properly fall within the scope of the appended claims.

Having described my invention what is claimed is:

40 1. A feeder of the character described comprising a platform, standards carried upon the upper side at diametrically opposite sides thereof and including inwardly offset portions adjacent their lower ends, a bowl arranged upon the upper side of the platform and having its opposite side edges frictionally engaging the inwardly offset portions of the standards, a band secured to the inner sides and adjacent the upper free ends of the standards, wires arranged upon the band at diametrically opposite sides thereof, and an inverted jar arranged within the band and having its neck extending within the bowl and restricted by the wires.

55 2. A feeder of the character described comprising a platform, a pair of standards secured to the upper side and at diametrically opposite points thereon and including inwardly offset portions adjacent their lower ends, a bowl arranged upon the upper sides 60 of the platform and having its opposite side edges engaging the inner side walls of the inwardly offset portions of the standards, a pair of retaining clips arranged upon the platform and having their upper edges bent over and frictionally engaging the periphery of the bowl, a circular band having its outer sides secured to the inner side and adjacent the upper ends of the standards, a pair of substantially inverted U-shaped wires having their lower free ends inwardly offset and intermediately supported upon the band and at diametrically opposite sides 65 thereof, and an inverted jar received within the band and having its shoulder engaging the inwardly offset portions of the substantially inverted U-shaped wires for restricting the entrance of its neck within the bowl.

70 3. A feeder of the character described comprising a platform, a pair of standards extending upwardly upon diametrically opposite sides thereof and including inwardly offset portions adjacent their lower ends, a bowl arranged upon the upper side of the platform and having its opposite side edges 75 engaging the inner sides of the inwardly offset portions of the standards, a pair of retaining clips arranged upon the opposite sides of the platform and having their upper ends bent over and frictionally engaging the periphery of the bowl, a relatively 80 flat circular band having its opposite edges bent inwardly upon themselves and secured to the inner sides and adjacent the upper ends of the standards, a pair of substantially inverted U-shaped wires having their lower free ends extending through pairs of channel members provided between the inner sides and inwardly bent edges of the band and their lower extremities being inwardly offset, and an inverted jar received within the inner sides of the band and having its shoulder engaging the inwardly offset portions of the wires for restricting the entrance of its neck within the bowl.

85 90 95 100 105 In testimony whereof I affix my signature.

EDWIN W. BOYER.
